ALBERT P. BROOME, OF YORK, PENNSYLVANIA.

SPARK-PLUG.

1,244,416.

Specification of Letters Patent. Patented Oct. 23, 1917.

Application filed January 12, 1916. Serial No. 71,685.

To all whom it may concern:

Be it known that I, ALBERT P. BROOME, a citizen of the United States, and a resident of York, in the county of York and State 5 of Pennsylvania, have invented certain new and useful Improvements in Spark-Plugs, of which the following is a specification.

My invention relates to an improvement in spark plugs for internal combustion engines and consists in the constructions, combinations, and arrangements of parts, herein described and claimed.

The principal object of my invention is the provision of a spark plug having the 15 embodiment of means whereby the electrodes are automatically cleaned of carbon deposits.

Another object of the invention lies in the use of substantially the same means for admitting charges of fresh air into the cylinder when the piston travels an intake stroke. When the piston performs a suction stroke, the charge of fresh air drawn in at that time will come along with and temper the gaseous charge.

25 A further object of the invention consists of the provision of a priming means.

Other objects and advantages will appear in the following specification reference being had to the accompanying drawing forming a part thereof in which:

Figure 1 is an enlarged elevation of the spark plug.

Fig. 2 is a central vertical section thereof.

Fig. 3 is a cross section along the line 35 3—3 of Fig. 2.

The spark plug includes a body or bushing 1 which is externally screw-threaded at 2 whereby it may be screwed into the cylinder head of an internal combustion engine 40 (not shown). The enlarged portion 3 of the bushing 1 is hexagonally shaped to afford convenient wrench grip when the plug is screwed in place.

The bushing 1 forms the grounded electrode of the plug and is formed at the bottom with an open ended bore wherein the insulated and co-acting electrode 4 is disposed. The above mentioned bore is widened at a place about midway of the length 50 of the bushing 1 to form a seat 5. The upper portion of the wall of the widened portion of the bore is threaded as at 6 to permit a clamping bushing 7 to be screwed therein, the bushing 7 also having a suitable 55 wrench receiving face, as shown in Fig. 1.

The porcelain insulator 8 is provided with

an annular shoulder 9 which rests on the seat 5, a suitable packing 10 being interposed between the surfaces. The porcelain 60 8 is secured in place by the clamping bushing 7 which engages the upper part of the shoulder 9 and forces the porcelain body to the seat 5. The lower end of porcelain 8 is formed with a portion 11 which is of a lesser diameter than the body of the porcelain, and is provided with a ground seat 12 against which the insulated electrode 4 normally rests.

A cup 13 is suitably cemented to the upper end of the porcelain insulator 8 and 70 virtually forms an integral part thereof, a passage 14 being produced on the longitudinal axis of the insulator as shown, the passage 14 beginning at the cup 13 and ending at the ground seat 12.

The terminal post 15 of the electrode 4, is disposed within the passage 14 but does not engage the walls thereof, the purpose in loosely mounting the terminal post in the passage 14 being to permit air to flow 80 through the passage during the operation of the engine and to this end the electrode 4 acts as a valve. The electrode 4 is normally held to its ground seat 12 by a tension spring 16 which is coiled about the upper 85 end of the post 15 and engages the porcelain 8 as shown. The other end of the spring 16 bears against a wing nut 17 which is fixed to the post 15 by a suitable pin after the proper tension of the spring 16 90 is once determined. Another wing nut 18 serves to clamp the wire from the distributor to the electrode terminal.

The suction caused by the engine piston when making an intake stroke, acts on the 95 electrode 4, drawing it down against the tension of the spring 16. This opens communication between the passage 14 and the engine cylinder and a charge of fresh air is drawn in, which commingles with the gases 100 and serves to improve the mixture. The repeated action of the electrode 4 which occurs on each intake stroke of the engine piston, becomes the active agency whereby deposits of carbon are loosened from the 105 spark forming parts. The air which is thus admitted, even if in small quantities, assists also in keeping these parts cool. The terminal 4 is provided with a pin 19 which passes through the terminal post 15 and the 110 electrode and projects on each side as shown; these projections form sparking points and

may be long or short as practice may require.

Having thus described my device the operation thereof is as follows:—When it is necessary to prime the engine, a quantity of gasolene is poured into the cup 13. When the engine piston makes its intake stroke it creates a suction in the cylinder chamber which acts on the valve-like electrode 4, drawing it away from its seat 12 and admitting a portion of the gasolene in the cup 13. The passage 14 is made ample enough to permit the gasolene to flow around the post 15.

15 The electrode 4 will soon re-seat itself and when the piston compresses the charge to the limit, a spark leaps across the gap between the terminals 4 and 1, and explodes the compressed charge. Each time that the piston 20 travels on its intake stroke, a suction is created which acts on the electrode 4 and urges it from its seat 12 against the tension of the spring 16 and thus a small amount of fresh air is admitted each time which not 25 only improves the mixture, but boosts the power and keeps the spark terminals cool.

The continued reciprocatory movement of the electrode 4 also dislodges any carbon which may have adhered to the parts and is 30 an active means in preventing the formation of carbon deposits around the plug.

I claim:—

1. In a spark plug for internal combustion engines, the combination of an insulating core having a bore therethrough, a valve for normally closing one end of the bore, a reservoir for a priming fluid connected with said bore, said valve being automatically opened at the intake stroke of the engine.
- 40 2. In a spark plug for internal combustion engines, an insulating core having an opening therethrough, a valve for normally closing the opening, a reservoir carried by the core at the opposite end thereof from the 45 valve, said reservoir being in communication with the opening, and said valve being automatically opened at the intake stroke of the engine piston.
- 50 3. In a spark plug for internal combustion engines, an insulating core having a longitudinal bore therethrough, a valve for nor-

mally closing one end of said bore, a sparking terminal carried by the valve, a terminal post secured to said valve and loosely disposed within said bore arranged for longitudinal movement, a spring carried by said terminal post for normally holding the valve on its seat, and a cup-carried by the core at the end opposite the valve and having communication with the bore.

4. A spark plug, comprising a bushing having one end internally threaded and provided with an annular internal shoulder, an elongated insulating body having a central bore and an annular shoulder and mounted 65 in the bushing, said body having a cup at one end and its other end reduced and forming a valve seat, a second bushing externally threaded and screwing into the first bushing, a terminal post loosely mounted in the bore 70 of the insulating body with its ends projecting beyond said body, a nut on the upper end of post, a spring on the post between the nut and the end of said body, and an electrode on the lower end of the post and forming a 75 valve adapted to be seated on the lower reduced end of the insulating body.

5. A spark plug comprising a bushing, an elongated insulating body mounted in the bushing and having a central bore, a reduced 80 lower end forming a valve seat, and a cup at its upper end into which leads the bore, a terminal post loosely mounted in the bore of the insulating body with its lower end projecting beyond the lower end of said body and its upper end projecting through said cup, a nut on the upper end of the post, a spring on the post between the nut and the end of the body, and an electrode on the lower end of the post and forming a seat 90 adapted to be seated against the lower end of the body.

6. A spark plug, comprising a bushing, an elongated insulating body mounted in the bushing and having a central bore and its 95 lower end formed into a valve seat, a loosely mounted and spring pressed terminal post in the bore of the insulating body, and an electrode on the lower end of the post and forming a valve and adapted to be seated on the seat at the lower end of said body.

ALBERT P. BROOME, JR.
